UNITED STATES PATENT OFFICE.

MARTINIUS STIXRUD, OF SEATTLE, WASHINGTON TERRITORY.

PLANING-MACHINE.

SPECIFICATION forming part of Letters Patent No. 399,711, dated March 19, 1889.

Application filed March 20, 1888. Serial No. 267,857. (No model.)

To all whom it may concern:

Be it known that I, MARTINIUS STIXRUD, of Seattle, in the county of King and Territory of Washington, have invented certain new and 5 useful Improvements in Planing-Machines, of which the following is a full and correct specification.

My invention relates to machines for planing timber adapted to horse or steam power; 10 and it consists of a rectangular body or block of wood made large enough to plane off heavy and thick timbers, first roughly hewn or sawed, combined with various mechanical parts, operating to make a machine which fulfills all 15 the requirements of a complete planer capable of both forward and backward movements.

By the mechanism which I employ my invention comprises apparatus for planing, for proper adjustment of the cutting-blade, for 20 easy and effective back motion, for regulating the planing operation, &c., and certain novel special contrivances, as hereinafter particularly set forth.

My planer is designed to be used in constructing wooden bridges and trestles and in 25 the planing and shaping of large and heavy timbers at the site of all structures where useful. Its employment saves the transportation of timbers to mills to be planed, and also saves 30 the time used up in planing them on the spot slowly and laboriously by hand-tools. My machine, while useful, generally, for planing, is also specially adapted to planing down 35 large timbers to any given or required size. In this special use my invention is used in combination with a bed of timber upon which the stick to be planed is laid, as hereinafter more fully detailed and described.

In the drawings hereto annexed and forming 40 a part hereof, wherein similar letters of reference refer to and indicate similar parts in the different figures, Figure 1 is a longitudinal vertical section of my invention through the broken line X X shown in Fig. 2 45 of the drawings, and exhibits all the parts of my invention that can be seen in such view as marked in the drawings. Fig. 2 is a plan view of my invention, showing the working parts therein indicated. Fig. 3 is a cross vertical section through the broken line Y Y of 50 Fig. 1. It shows the rollers R R and certain

other parts, as hereinafter particularly specified, the supports H H of Fig. 1 being removed.

The main body of my invention, preferably made of wood, is marked A in the drawings. 55 I generally construct it about six feet long, twenty-two inches wide, and six inches thick, although other proportions could be used to suit the purpose. Through this body I cut a triangular opening, O, into which is fitted a 60 cast-iron pocket, C, of one piece, flanged as shown in the drawings, carrying projections y y over the blades B and B' for the wedges W W, and the two sockets p p under the blade B, with an opening, o, in the bottom of 65 the pocket to let the blade B and the shavings through. This pocket I fasten to the wood of the body with bolts through the flanges.

B is the main blade, which does the cutting or planing and lies in operation along the beveled side of the pocket, extending through the opening o in the bottom of the pocket. Upon the main blade is the counter-blade B', of the 70 same width as the main blade. This counter-blade is fastened to the main blade by 75 means of two screws, S S, and the counter-blade is slotted at these two screws so as to adjust the counter-blade on the main blade. The two blades are fastened to the pocket-casting by means of the two screws S' S' and 80 85 tightened thereto by the two wedges W W, which enter between the counter-blade and the projections y y over the blades of the pocket-casting. (See Fig. 2 of the drawings.) The two screws S' S' pass through slots x x in both blades, and are screwed into the pocket-casting in any convenient manner. These screws tighten the blades B and B' to the pocket-casting. I preferably make them ratchet-headed, so as to be turned with a special 90 wrench.

My blades are naturally made rather broad ones, and the slots in them, through which the tightening-screws pass and act, are placed at or near the longitudinal center line of the 95 blades. The sides of the blades are inclined to spring up under the action of the tightening-screws. Such upspringing my wedges W W are purposely designed to overcome, and by them the blades will be the more firmly 100 pressed down upon the inclined surface of the pocket. The wedges are valuable auxiliaries

to the tightening-screws, in that they more equally distribute the pressure, keep the broad blades flatter and secure a closer contact for them, give them greater rigidity, and increase 5 their firmness and efficiency.

The adjustment of the main blade is made by means of the two screws D D, which are held stationary, except that they turn around their own axes. The screws D D are made 10 thus stationary by means of two sockets, p p, for them in the pocket-casting, and to prevent the screws from lifting up there is a bed-plate, K, bolted to the body of the machine, (see Fig. 1,) carrying two supports, H H, on each 15 side of the body. Each set of such supports terminates in a journal, J. The screws D D each pass through a journal. Under each journal, on the screw, is fastened a collar, L, by means of a key of steel, or otherwise, which 20 prevents the uplifting of the screws D D. These screws D D also each pass through a nut, N. (See Fig. 1.) There are two of these nuts N N. These nuts N N each terminate in a screw that passes through the longitudinal 25 slots S'' S'' in the main blade, near its top, and are fastened to this blade by nuts n n on the screws. The slots S'' S'' admit of taking the main blade out of the machine when loosened up. In adjusting the cutting end of 30 the main blade the tightening-screws and wedges are loosened, the screws D D turned, and then the nuts N N, with the main blade, will move up and down, thus obtaining the required adjustment. In pulling the planer 35 back upon the timber after it has planed a length, the two rollers R R, (shown in Fig. 3, also in Fig. 1 dotted, which rollers in the forward movement of the machine were held up far enough in the body of the machine not to 40 touch the stick of timber planed) are thrown down from the machine in the manner herein-after particularly set forth, and the machine is pulled back on them to begin the planing movement again. These rollers are purposely 45 placed at or near the center of the body A, as shown in Fig. 1, so as to balance the planer. The rollers R R move around an axle, q, which I fasten to two levers, V V. These levers are fitted into the body of the machine, 50 so that their outer surfaces are flush with the outer surface of the body, and the levers are movable around the stationary axle z. The rollers and the levers are held up in the machine by means of the handle M in the center 55 of the machine, which handle holds up the horizontal rod T, connecting the two levers. This handle M is peculiarly shaped, with a double shoulder or projection, as shown in Fig. 1 of the drawings. When it is desired 60 to throw the rollers down below the machine, the handle M is pulled back by the operator, which movement unhooks the horizontal rod T from the upper shoulder of the handle M, as seen in Fig. 1. This rod with the levers is 65 then forced down and catches on the lower shoulder of the handle M, (seen in Fig. 1,) and is held there. The spring Q presses the

handle M forward and prevents the rod from being detached from the shoulder and letting up the rollers. To lift up the rollers, the handle M is pulled back again by the operator, and the horizontal rod T, connecting with the rollers through the levers V V, is lifted up and is caught upon the upper shoulder of the handle M.

On both sides of the body of the machine run iron flanges (marked F F) the length of the planing-machine itself, the uses of which are to guide the machine on the stick of timber to be planed, and also to regulate the size 80 or thickness to which the timber shall be cut by stopping the cutting or planing when the required size or thickness has been attained. These flanges are bent inward under the planing-blade and body of the machine, and extend inward, forming angle-irons, so that the distance between the flange-points is equal to the width of the blade. On the outside of these flanges are fastened pieces of wood, P P, as long as the flanges, flush with the lower surfaces of the flanges, which arrangement gives large guiding-surfaces on both sides of the machine. These flanges are made adjustable by means of the slots g g in the flanges, through which the clamping-bolts I I pass. In planing a stick to a certain size the stick is laid 85 in a bed of timber under the machine with two longitudinal sills of ascertained height placed right under the adjusted flanges, and the planer will cut the stick until the adjusted flanges touch the longitudinal sills.

I am aware that Jacob Siegley, in Patent No. 269,967, employed one blade-adjusting screw or spindle, which operated on or in cast bearings or appurtenances of the plane-stock, 105 differently constructed, however, from my bearings or my sockets, the worm-screws of which adjusting-screws engaged in serrations (transverse) of the cutting-blade to adjust it. I am further aware that William Tidgewell, 110 in Patent No. 312,229, operated one blade-adjusting screw supported in a peculiar manner upon or in cast bearings of the plane-stock, with a nut upon the screw constructed to engage the cutting-blade under the counter-blade and adjust it, this nut being prevented 115 from turning with the adjusting-screw by certain applied guides. I disclaim both these constructions. I employ bearings for the adjusting-screws differing from both. I employ 120 adjusting-screws provided with attachments differing from both; and I do not engage the cutter as either Siegley or Tidgewell do. My adjusting apparatus, with its stock bearings and attachments, is, *sui generis*, constructed 125 as I show and explain it, so as to render it both independent or self-acting and yet at the same time a harmonious component of a complete planer. I do not employ a worm-screw at all, and my cutter is not serrated. My 130 screw-nuts engage the cutter not through or under the counter or clamping blade, but above and independently of the counter-blade, and they engage it not by mere studs passed

into the blade, but by nut projections, which pass entirely through slots S'' S'' of the cutter above the counter-blade, and are secured by small nuts or tops. My cutter is slotted above the counter-blade. Neither Siegley's nor Tidgewell's is. My constructions are such that they properly co-ordinate all my planing mechanism. My adjusting-screws are not fixed as to longitudinal movement by nut-guides, but by collars fastened under the screw-journals co-operating with the screw-nuts and pocket-sockets. While one adjusting-screw centrally positioned as to the cutter might be sufficient for narrow blades and light planing work, in cases of heavy cutting, for which my machine is particularly designed, large broad blades must be used. It then becomes an imperative mechanical requirement that the adjustment of the blade's cutting-edge be made all along particularly true or exact; hence a double set of strong adjusting-screws and suitable auxiliary mechanism—such as I novelly employ—should be used, engaging the cutter conveniently on both sides of its longitudinal center, furnishing a broad true cutting-edge to the blade.

Having thus fully described my invention, what I claim as new or novel herein, and desire to secure by Letters Patent from the United States, is as follows:

1. In a planer, the planing apparatus consisting of the block A, flanged pocket C, having blade-opening o, and carrying wedge projections over the blades, and the sockets p p in the casting, the blade B, provided with slots x x and slots S'' S'', counter-blade B', provided with slots x x, screws S' S', wedges W W, bed-plate K, carrying two sets of supports, H H, and journals J J, the screws D D, carrying collars L L, and nuts N N, provided with nuts n n, the rollers R R, axle q, levers V V, stationary axle z, horizontal rod T, handle M, spring Q, flanges F F, provided with slots g g and clamping-bolts I I, and the guide-pieces P P, substantially as herein described.

2. In a planer, the block A, in combination with the flanged cast-iron pocket C, provided with wedge projections y y over the blades and formed with blade-opening O and sockets p p in the casting, the blade B, provided with the slots x x and slots S'' S'', the counter-blade B', provided with slots x x, the wedges W W, screws S' S', the bed-plate K, carrying two sets of supports, H H, and journals J J, the screws D D, carrying collars L L, and nuts N N, provided with nuts n n, acting upon the blade B through the slots S'' S'', substantially as herein set forth.

3. In a planer, the combination, with block A, formed with opening O, of the flanged cast-iron pocket C, fitted into said opening, said pocket C provided with wedge projections y y over the blades B B' for the wedges W W, blade-opening o for the blade B, and sockets p p for the adjusting-screws D D in the casting, substantially as herein set forth.

4. In a planer, the combination, with pocket C of block A, said pocket formed with wedge projections y y, and the blades B and B', of the wedges W W, which operate in said wedge projections y y of said pocket over the blades, substantially as herein shown.

5. In a planer, the block-pocket C, provided with sockets p p in the casting, and the planing-blade B, provided with slots S'' S'' above the counter-blade, in combination with adjusting-screws D D, screw-nuts N N, projected through said blade-slots, and the nuts n n, substantially as herein shown.

6. In a planer, the combination, with the cutting-blade B, slotted above the counter-blade B', of an independent bed-plate, K, attached to the top of the block A, and provided with two upright sets of supports, H H, having journals J J, and the collared screws D D and their parts, and the nuts n n, adjustable in the slots of the cutting-blade, constituting the adjusting mechanism or means for properly supporting and co-ordinating the said screws in the adjustment of the cutting-blade above the counter-blade, substantially as herein shown.

7. In a planer, the adjusting mechanism for the planing-blade, consisting of the combination, with block A and blade B, provided with slots S'' S'' above the counter-blade, of the pocket C, provided with sockets p p in the casting, bed-plate K, attached to the block, double supports H H upon the bed-plate, the screws D D, provided with collars L L, and projected nuts N N, provided with other nuts, n n, which said projected nuts operate through the blade-slots S'' S'' above the counter-blade, all substantially as herein set forth and explained.

8. In a planer, the combination, with the block A and its adjustable planing apparatus, of the rollers R R, axle q, levers V V, stationary axle z, horizontal rod T, double-shouldered handle M, and spring Q, coacting to move the planing-machine backward after a progression or propulsion, substantially as herein set forth.

9. In a planer, the uplifting and depressing mechanism for the rollers R R, consisting of the combination, with the block A, of the levers V V, stationary axle z, horizontal rod T, handle M, and spring Q, acting upon the rollers, substantially as herein set forth.

10. In a planer, the combination, with the block-rollers R R, movable around the axle q under the block A, of the uplifting and depressing roller mechanism, consisting of the levers V V, axle z, and rod T, and the handle M, double-shouldered for retaining the rod T in each of its positions, and the spring Q, all substantially as herein described.

11. In a planer having rollers and roller-operating handles, the mechanism for connecting the operating-handle with the rollers, consisting of levers attached to the axle of the rollers and movable around a stationary axle, in co-operation with the rod T, uniting the levers, substantially as herein shown.

12. In a planer constructed with the roller-operating handle M, and having levers attached to the roller-axle, as shown, the rod T, uniting such levers and connecting them 5 united with the operating-handle, substantially as herein set forth.
13. In a planer having rollers, the double-shouldered handle M for operating the roller mechanism, substantially as herein described.
14. In a planer of the character described, the combination, with the double-shouldered handle M and the roller mechanism set forth, of the spring Q for rendering the roller mechanism undetachable from the operating handle, substantially as herein shown.
15. In a planer, the flanges F F, provided with slots g g, said flanges so constructed as to run on both sides of the block A the length of the block, and the clamping-bolts II, 20 which pass through the block and the flange-slots, said flanges bent inward under the block A and forming angle-irons and adjustable under the block A, and the guide-pieces P P, attached to the flanges F F and flush with 25 their lower surfaces, substantially as herein described.
16. In planers, the combination, with block A and cutting-blade B, of the adjustable flanges F F, provided with slots g g and clamping-bolts II, passing through the slots, said flanges bent inward under the block, forming angle-irons and carrying the guide-pieces P P, made as long as the flanges and flush with their lower surfaces, all substantially as herein shown. 30
17. The combination, with planers having adjustable flanges of the character described, of the attached flanged guide-pieces P P, made as long as the flanges and flush with their lower surfaces, constituting an arrangement 40 which gives large adjustable guiding-surfaces on both sides of the planer, substantially as herein set forth.

In testimony that I claim the foregoing I have hereunto set my hand, this 9th day of 45 March, 1888, at Seattle, King county, Washington Territory, in the presence of two witnesses.

MARTINIUS STIXRUD.
